HOCKEY STICK

Raymond W. Leclerc, Leominster, Mass.
(% Mylec Inc., Winchendon Springs, Mass. 01475)

Filed Aug. 5, 1974, Ser. No. 494,561

Term of patent 14 years

Int. Cl. D21—02

U.S. Cl. D34—5 BC

FIG. 1 is a side elevational view of a hockey stick showing my new design; and

FIG. 2 is an edge view thereof looking in the direction of arrow 2 in FIG. 1. The opposite aspect of the design is a mirror image.

I claim:

The ornamental design for a hockey stick, as shown and described.
